UNITED STATES PATENT OFFICE.

CHARLES GRONSKI, OF SHERIDAN, WYOMING.

CRAMPING DEVICE.

Original application filed February 12, 1926, Serial No. 87,963. Divided and this application filed July 3, 1926. Serial No. 120,405.

My invention relates to the manufacture of shoes, and more particularly to an improvement in cramping devices, and it consists in the combinations, constructions and arrangements herein described and claimed.

The present application is a division of my prior pending application, Serial #87,963, filed February 12, 1926, for cramping device and shoes.

10 An object of the invention is the provision of a simple, reliable and efficient cramping device for holding the leather main body portion of a shoe upper stretched and in a desirable shape so that a shoe which includes said main body portion of the shoe upper will fit the foot for which it is intended smoothly and accurately.

15 A further object of the invention is the provision of a cramping device of the character described which can be adjusted quickly and easily either to hold the leather main upper body of a shoe upper or to release the leather body, as desired.

20 Other objects and advantages of the invention will be apparent from the following description, considered in conjunction with the accompanying drawings, in which—

Figure 1 is a perspective view of the improved cramping device in use, and

25 Figure 2 is a horizontal section through the cramping device.

30 The improved cramping device includes a pair of clamping arms 1 which are hinged together at their outer ends, as at 2, to swing about an axis which extends at right angles to the direction of length of each of the arms. The inner or adjacent faces of the opposite end portions of the arms 1 are roughened, as by being formed with transversely extending teeth 3. Each arm 1 is provided with a pair of laterally extending arms 4 at the side thereof which is nearest to the other arm, the ears 4 of each pair being aligned transversely of the arm on which they are mounted and being provided with aligned openings, as at 5, for a purpose to be presently described.

35 The pairs of ears 4 are located at the outer ends of the toothed portions of the arms and these arms may be apertured transversely, as at 6, by openings or slots which extend between the ears 4 of the respective pairs and outwardly in the arms for the greater part of the length of the arms.

A jaw member 7 is swingingly supported between the ears 4 of one of the arms 1 by means of a pivot element 8 which extends through the aligned openings 5 of the ears of one of the members 1 and through the 60 jaw member 7 intermediate the length of the latter, whereby the outer end portion of the jaw member 7 will be swingable in the transverse aperture 6 of the associated arm 1 and the opposite end portion of the jaw member 7 is disposed in confronting relation to the toothed end portion of the associated arm 1 and is provided with transversely extending teeth, as at 9, on its outer face for cooperating with the teeth 3 of the 65 jaw portion of the associated arm 1 to grip a piece of leather or like object which has been thrust between the toothed jaw portion of the member 7 and the toothed or jaw portion of the associated arm 1.

70 A jaw member 10 is supported intermediate its length between the ears 4 of the second arm 1 by means of a pivot element 11 so that the outer end portion of the member 10 will be swingable in the transverse 75 aperture 6 of the second arm 1 and the opposite end portion of the member 10, which has transverse teeth at 12 in its outer face, will be disposed in position to cooperate with the toothed end portion or jaw of the 80 second arm 1 to grip an object which has been placed therebetween. The outer end portion of the jaw member 10 is pivotally attached, as at 13, to an end of an operating rod 14 which extends through the aperture 85 90 6 of the arm 1 which supports the jaw member 7. The operating rod 14 also extends loosely through a transverse opening 15 in the outer end portion of the jaw member 7. A substantially wedge-shaped washer or 95 thrust member 16 is freely slidable on the outer end portion of the rod 14 and bears against the outer face of the adjacent arm 1. The rod 14 is provided with screw threads for the greater part of its length 100 105 for engagement with an adjusting nut 17 which bears against the washer 16 and which preferably is provided with a laterally extending crank handle, as at 17, whereby the nut can be turned quickly and easily on the rod 14.

The parts which have been described so far preferably are made of metal.

110 The cramping block or last 19 is formed of wood or other suitable material and is

shaped to have substantially the form of a foot for which the shoe is to be made. The instep portion of the block 19 has shallow depressions formed therein at opposite sides 5 of the instep, as at 20, for the reception of the extremities of the jaw portions of the jaw members 7 and 10, as illustrated to advantage in Fig. 2.

The operation of the cramping device is 10 substantially as follows:

The piece of leather 21 which will form the main body portion of a shoe upper is fitted on the block 19 after the leather piece 21 has been soaked for approximately 20 15 minutes in water so that the side edges of the piece of leather 21 will be disposed at the front of the block. One of these side edges of the piece of leather 21 is placed between the jaws which are carried by one of 20 the arms 1 while the other side edge portion of the piece of leather 21 is inserted between the jaws of the other arm 1. Small pieces of leather, as at 22 may be placed between the outer faces of the main piece of 25 leather 21 and the teeth of the adjacent jaws, to prevent marring or cutting of the outer faces of the side edge portions of the leather member 21. At this time, the extremities 30 of the jaw members 7 and 10 will be seated in the cavities 20 and the jaws which are carried by the respective arms 1 will be tightened so that the side edge portions of the piece of leather 21 will be firmly gripped when the nut 17 is turned on the rod 14 as 35 required to force the adjacent arm 1 toward the second arm 1. The piece of leather 21 then will be placed under tension which will stretch the leather sufficiently to cause it to accurately conform to the cross sectional configuration of the block 19. The piece of 40 leather 21 therefore will be shaped as required to fit the block 19 smoothly, particularly the portion of the block 19 which has the shape of the ankle portion of the foot 45 for which the shoe that is to be made is intended. After the member 21 has been stretched to shape on the block 19 in the manner just described, edge portions thereof may be tacked to the block, as at 23, and 50 the piece of leather 21 is left in place on the block for a desirable period which probably will be about 24 hours. Permanent set of the stretched and shaped piece of leather 21 then will have been effected and the member 55 21 when released from the pairs of jaws of the cramping device and removed from the

block will have a shape which will adapt it particularly for use as the body portion of the upper of a shoe that will fit the foot smoothly and accurately. 60

The hereinbefore described cramping device is particularly well adapted for use in forming a shoe including an upper having no vertical seams at the back and being particularly well shaped so as to smoothly fit 65 the foot for which it is intended.

Obviously, the invention is susceptible of embodiment in forms other than that which is illustrated in the accompanying drawings, and I therefore consider as my own all such 70 modifications and adaptations thereof as fairly fall within the scope of the appended claim.

I claim:

In a shoe cramping device, a pair of arms 75 hinged together at their outer ends and having stationary jaws at their other ends, the adjacent faces of said stationary jaws having transverse teeth, and said arms having pairs of spaced ears at their adjacent sides 80 outwardly of the toothed portions, other jaw members pivotally supported intermediate their length between the ears on said arms, each of said last named jaw members having transverse teeth on its outer face in confronting relation to the teeth of the jaw portion of the associated arm and being adapted to cooperate with the jaw portion of the associated arm to grip a piece of leather or like object which has been placed therebetween, said arms having transverse apertures outwardly of said ears for the reception of the outer end portions of said second named jaw members, the outer end portion of one of said second named jaw members 85 having a transverse aperture, an adjusting rod pivotally attached at one end to the other jaw member at the outer end of the last named jaw member and extending through the aperture of the apertured second named jaw member, the free end portion of said rod extending through the aperture in the arm which supports said apertured second named jaw member, a washer slidable on the rod against the outer face of the adjacent arm, and a nut in threaded engagement with said rod and bearing against said washer, said nut being adjustable to cause swinging movement of said arms toward each other and to cause closing of the jaws 100 of one of said arms. 105

CHARLES GRONSKI.
